(57) **CLAIM**

The ornamental design of apparatus for sleep information detection, as shown and described.

DESCRIPTION

FIG. 1 is a top, front and left side perspective view of an embodiment of an apparatus for sleep information detection; FIG. 2 is a front elevation view thereof; FIG. 3 is a rear elevation view thereof; FIG. 4 is a left side elevation view thereof, the right side being a mirror image; FIG. 5 is a top plan view thereof; FIG. 6 is a bottom plan view thereof; FIG. 7 is a top, front and left side perspective view of an embodiment of a detection module of the apparatus for sleep information detection of FIG. 1; FIG. 8 is a top, rear and right side perspective view thereof; FIG. 9 is a front elevation view thereof; FIG. 10 is a rear elevation view thereof; FIG. 11 is a right side elevation view thereof; FIG. 12 is a left side elevation view thereof; FIG. 13 is a top plan view thereof; FIG. 14 is a bottom plan view thereof; FIG. 15 is a top, front and left side perspective view of an embodiment of a stand of the apparatus for sleep information detection of FIG. 1; FIG. 16 is a front elevation view thereof; FIG. 17 is a rear elevation view thereof; FIG. 18 is a left or right side elevation view thereof; FIG. 19 is a top plan view thereof; FIG. 20 is a bottom plan view thereof; FIG. 21 is a top, front and left side perspective view of another embodiment of a stand of the apparatus for sleep information detection of FIG. 1; FIG. 22 is a front elevation view thereof; and, FIG. 23 is a rear elevation view thereof. The broken lines in the drawings are included for purposes of illustrating portions of the apparatus for sleep information detection that form no part of the claimed design.
